UNITED STATES PATENT OFFICE.

WINFIELD S. THOMAS, OF BOSTON, MASSACHUSETTS, ASSIGNOR OF ONE-HALF TO THE WHITIN MACHINE WORKS, OF WHITINSVILLE, MASSACHUSETTS.

LOOM.

SPECIFICATION forming part of Letters Patent No. 617,811, dated January 3, 1899.

Application filed December 15, 1897. Serial No. 661,935. (No model.)

To all whom it may concern:

Be it known that I, WINFIELD S. THOMAS, of Boston, in the county of Suffolk and State of Massachusetts, have invented a new and useful Improvement in Looms; and I hereby declare that the following is a full, clear, and exact description of the same, reference being had to the accompanying drawings, forming part of this specification.

10 This invention relates to improvements in shuttle-changing mechanism for looms, by which when the weft-thread is exhausted or broken the shuttle is automatically discharged and replaced by another shuttle.

15 In weaving cloth the weft-thread is carried by the shuttle through the open shed of the warp from one side to the other to lay the weft-thread, which when laid tilts the weft-fork and raises the rear end above the weft-hammer of the stop mechanism. When the weft-thread is absent, the weft-fork is not tilted, the rear end engages with the said weft-hammer, and in looms provided with automatic shuttle-changing mechanism operates 20 the same to discharge the shuttle the filling-thread of which is broken or exhausted and supply a new shuttle. The lay of a modern loom makes many strokes in a minute, and the cloth is taken up at each stroke of the lay.

25 To prevent thin places in the cloth, the shuttle in which the filling-thread is broken or exhausted must be replaced by a fresh shuttle as quickly as possible.

30 In the shuttle-changing mechanism described hereinafter and illustrated in the drawings the slide supporting the weft-fork is moved forward by the vibrating lever operated constantly by a cam on the cam or lower shaft of the loom in the manner usual 35 with stop-motions used on looms to stop the loom when the weft-thread is not laid, and in the same manner as is usual in these well-known stop-motions. The said slide bears against an arm secured to and extending upward from the usual detector rock-shaft, extending from side to side under the breast-beam and supported in suitable journal-bearings secured to the breast-beam. Near the opposite end of the detector rock-shaft an arm 40 provided at its outer end with an inclined cam operates a bell-crank lever, which as the lay moves away from the breast-beam un-

locks the bottom plate or gate of the shuttle-box on the lay, and the gate opens and a deflector connected with the gate enters the shuttle-box from above and guides the shuttle, which is thrown from the opposite shuttle-box by the picker-stick, downward into a suitable receptacle. An arm on the same end of the detector rock-shaft connected with a constantly-reciprocating arm operated through a bell-crank lever from the lower or cam shaft raises the end of the constantly-reciprocating arm and connects it with a pin to operate the shuttle-carrier and swing the same toward the lay, so as to enter the uppermost shuttle into the shuttle-box, the gate of which is being raised by a bell-crank lever, and at the instant when the lay reaches the limit of the forward movement the bottom 55 plate or gate of the shuttle-box is latched. As the lay swings backward the shuttle-carrier swings forward, and a shield covering the periphery of a ratchet-wheel secured to a shaft which forms the fulcrum of the shuttle-carrier and provided with a sprocket-wheel is moved to permit a pawl to enter the ratchet-wheel and turn the shaft, thereby 60 communicating motion to the chain carrying the shuttles and moving the next shuttle into 65 the upper position ready to enter the shuttle-box when required. All the parts of the shuttle-supplying mechanism are now again in their normal position ready to discharge a shuttle the weft-thread of which 70 may have broken or exhausted and supply a 75 fresh shuttle.

Figure 1 is a side view of part of a loom, showing the crank-shaft, the lower or cam shaft, the lay, the shuttle-carrier, and the operative mechanism connecting the same. Fig. 2 is a front view of one end of the loom, showing the shuttle-supplying mechanism. Part of the breast-beam is broken away so as to show the mechanism behind the same more 90 clearly. Fig. 3 is a transverse vertical section of the front part of the loom, showing the mechanism connected with the detector rock-shaft and operated by the cam-shaft by which the shuttle-supplying mechanism is 95 connected to operate automatically when the shuttle has failed to lay the weft-thread. Fig. 4 is a top or plan view of the front portion of 100 one end of the loom, the crank-shaft being

omitted, so as to show the cam-shaft and the connections with the same more clearly. Fig. 5 is a top or plan view of the mechanism for actuating the shuttle-carrier and the shuttle-supporting chain. Fig. 6 is a top view, on an enlarged scale, of the rock-shaft by which the motion of the permanently-reciprocating arm is transmitted to the shuttle-carrier when the arm is raised and connected with the pin. Fig. 7 is a side view, on an enlarged scale, of the bracket supporting the shuttle-carrier and mechanism for operating the same, shown also in Fig. 1. Fig. 8 is a top view, on an enlarged scale, showing the shield covering the ratchet-wheel and the lever for controlling the shield in the two opposite positions. Fig. 9 is a side view, on an enlarged scale, of the ratchet-wheel connected with the shaft of the chain sprocket-wheel by which the shuttles are advanced, showing the pawl and the shield in broken and solid lines in opposite positions and above the same the permanently-reciprocating arm and the pin on the rock-shaft, also shown in Fig. 6. Fig. 10 is a vertical end view showing the mechanism for unlocking the bottom or gate of the shuttle-box and the swell mechanism connected with the gate and operated by the same in solid and in broken lines in opposite positions. Fig. 11 is a top or plan view of the mechanism shown in Fig. 10. Fig. 12 is a vertical transverse sectional view of the breast-beam, the lay, and mechanism connected therewith, showing the lay in the position with the gate open when discharging a shuttle in solid lines and in the position when a new shuttle has been supplied and the gate locked in broken lines. Fig. 13 is a plan view showing a portion of the breast-beam, the lay, and the mechanism for unlocking the bottom or gate of the shuttle-box.

Similar numerals of reference indicate corresponding parts in all the figures of the drawings.

45 In the drawings the numeral 1 indicates the end frame of the loom; 2, the front strut, extending from one end frame to the other; 3, the breast-beam; 4, the crank-shaft, and 5 the lower or cam shaft; 6, the fulcrum-shaft, on which the lay is supported; 7, one of the swords extending from the fulcrum-shaft to the lay; 8, the lay, and 9 the pitman connecting the lay with the crank of the crank-shaft.

55 In Fig. 12 the weft-fork 10 on the farther end of the breast-beam is shown pivotally connected with a slide 10', which when the weft-fork is not tilted by the weft-thread is moved by the weft-hammer 10² and operates, through the arm 11, the detector rock-shaft 60 12, which extends under the breast-beam from one side of the loom to the other, the arm 13 secured to the detector rock-shaft at the shuttle-changing side of the loom. The inclined cam 14 on the arm 13 engages with 65 a similar cam 14' on the bell-crank lever 15 and tilts the same against the strain of a coiled spring 14², connected with one arm of

the bell-crank lever to maintain the same in the normal position. The tilting of the bell-crank lever depresses the forward projecting 70 arm 16, which at that instant of time has entered an opening in the lay and as the lay moves away from the breast-beam encounters with its inclined end the end of a pin connected with the latch 17, as is clearly shown 75 in Fig. 13. The latch 17 serves to hold the gate 18, which forms the bottom of the shuttle-box carried on the lay. The gate 18 is hinged on its rear side to the rod 18' on the shuttle-box and when released drops downward to open the bottom of the shuttle-box. The deflector 19 is pivotally supported on the shuttle-box above a slit 19', through which it may enter the shuttle-box. The tailpiece 20 of the deflector 19 is connected to the slotted 85 lever 21, journaled in a bracket extending above the shuttle-box. The lever 21 is provided with the swivel 22, and this is connected with the gate 18 by the connecting-rod 23, so that when the gate is unlatched it swings 90 open and through the connecting-rod 23 and lever 21 raises the tail end of the deflector 19 and carries the deflector into the shuttle-box to guide the shuttle, which at this time is thrown from the opposite end of the lay downward to be discharged through the bottom and guided by the gate toward the breast-beam into a suitable receptacle placed below the shuttle-box.

The shuttle-box 24 is open on the side toward the breast-beam, and as the shuttles are inserted into the shuttle-box from this side the swell 25 is placed on the upper side of the shuttle-box and bears on the upper side of the shuttle, holding the shuttle in the shuttle-box during the backward vibration of the lay. The lever 25, which controls the swell, is pivoted in a bracket secured to the shuttle-box and has the opposite end connected by the link 26 with the rocking arm 27, the forked end 28 of which engages with a pin on the arm 29 of the gate 18. The edge of the rocking arm 27 near the forked end has the concave 27' to correspond with the rounded edge 30 of the hinged side of the gate 18, so that when the opening of the gate has carried the forked end 28 into the position shown in broken lines in Fig. 10 the rocking arm 27 will be retained in this position by the contact of the concave portion of the rocking arm with the convex edge 30 of the gate 18 with the end of the swell 25' raised and permits the gate to fully open. When the gate is closing, the pin on the arm 29 enters the fork 28 and operates the rocking arm 27 and through the link 26 the lever 25 to lower the end of the swell 25'.

The shuttle is thrown in the usual manner by the picker-stick 31 on the side of the loom opposite the side where the shuttles are supplied and is discharged through the open gate 13 at or about the farthest inward movement of the lay, and the gate is gradually raised as the lay moves forward to be secured by the latch at the end of the outward stroke of the lay.

To secure this movement, the gate 18 is provided with the roll-bearing 32, which as the lay moves forward rides on the arm 33 of the bell-crank lever 34. The end of the arm 33 is formed into a quick-rising cam 33', which acts to raise the gate to the locked position at the end of the forward movement of the lay. The opposite end of the bell-crank lever 34 is provided with the heel-plate 35, having slots, 10 and is secured to the slotted end of the bell-crank lever 34 by bolts, so that it may be adjusted vertically and horizontally. The heel-plate has the roller 36, which bears on the cam 37, secured to the cam-shaft 5. The 15 shape of the cam 37 is preferably such as will give to the bell-crank lever 34 and the gate 18, controlled by it, the desired movement to permit the entrance of a shuttle into the shuttle-box and the latching of the gate as 20 the lay, with the shuttle-box, moves forward.

The shuttles are supplied to the shuttle-box on the lay by the shuttle-carrier 38, consisting of a bracket supported on the shaft 39. The upper part of the bracket is bifurcated, one part forming the journal-support of the shaft 40 and the other the bearings for the shaft 41. These shafts are provided with sprocket-wheels 40' and 41', respectively, by which the endless chains 42 42 are operated. 25 The links of the chains 42 42 are provided with spring-clamps 43, on which the shuttles 44 44 are placed and are carried successively forward until they reach the position of the shuttle 44', as shown in Fig. 1. On the shaft 39 30 is also placed a sprocket-wheel 40², over which passes the endless chain 45, extending over a sprocket-wheel 40³, secured to the shaft 39, so that the turning of the shaft 39 transmits motion through the chain 45 to the chains 42 42 and to the shuttles carried on these 35 chains. The shuttle-carrier 38 and the chains and shuttles carried by the same are given, when a shuttle is to be supplied to the shuttle-box to replace the shuttle discharged, a 40 swinging motion toward the approaching shuttle-box on the lay sufficient to carry the shuttle into the shuttle-box and over the gate as the lay reaches the forward limit of its throw. The gate now swings upward and 45 raises the shuttle off from the shuttle-carrier and upward into the shuttle-box. When the gate is closed and latched, the shuttle-carrier is made to swing forward to resume the normal position, as shown in Fig. 1.

The mechanism for swinging the shuttle-carrier 38 is operated by the cam 46, secured to the cam-shaft 5. The bell-crank lever 47 is provided with a roll which bears on the cam 46. In the preferred form, as shown in Fig. 60 3, a grooved cam is used to control the bell-crank lever; but a spring may be used in the usual manner to hold the heel of the bell-crank lever in contact with the cam. The arm 48 is connected at one end with the bell-crank lever 47 and at the other end by the connecting-rod 49 with the arm 50, secured to the detector rock-shaft 12 near the arm 13.

The arm 48 has near its forward end the seat 51 and on one side of the seat the shoulder 52. When the detector rock-shaft is partially turned by the weft-fork slide, the arm 50 raises the forward end of the arm 48 and the seat 51 engages with the crank-pin 53 and the backward movement of the arm 48 carries the pin 53 with it and partially turns by the crank 54 70 75 the shaft 55, to the opposite end of which the crank 56 is secured and provided with the crank-pin 57, which extends through a slot in the plate 58, secured to the shuttle-carrier 38 above the rocking support of the carrier on 80 the shaft 39, thereby swinging the shuttle-carrier from its normal position, as shown in Fig. 1, and carrying the shuttle 44' into the shuttle-box. As the detector rock-shaft resumes its normal position the arm 50 is lowered, the seat 51 is disengaged from the pin 53, and the shoulder 52 bears on the pin 53 as the arm 48 moves forward, thereby turning the shaft 55 and swinging the shuttle-carrier back into the normal position. The shuttle 90 95 44' having been placed into the shuttle-box, the chains 42 42 have to be operated to move the shuttles forward so as to bring another shuttle into the position of the shuttle 44' by giving to the shaft 39 a quarter-turn. To this 95 end the ratchet-wheel 59, provided with four preferably hooked teeth, is secured to the shaft 39, the arm 60 is journaled on the shaft 39 close to the ratchet-wheel 59, the pawl 61 is pivotally and preferably adjustably secured 100 to the arm 60, and to the arm is secured, in the preferred form adjustably, one end of the rod 62, the other end of which is secured to the bell-crank lever 63, the heel of which engages with the cam 64, secured to the cam-shaft 5, so that at each turn of the cam-shaft 105 64, the pawl 61 will move forward, engage with a tooth, and in moving backward will turn the ratchet-wheel 59 one quarter-turn, and with it the shaft 39, to operate the chain 45, 110 and by it the chains 42 42 and the shuttles carried by them to advance the shuttles a distance equal to one shuttle.

To regulate and control the forward movement of the shuttles, the shield 65 is interposed between the pawl and the ratchet-tooth with which the pawl would engage were the shield removed. The shield 65 is supported on the arm 66, counterweighted by the weight 67 and provided with a projection 67', co-operating with the stop 68; adjustably secured to the fixed support of the shaft 39. In its normal position, as shown in Figs. 2 and 9, the shield 65 covers one tooth and the pawl 61 rides on the shield. When the shuttle-carrier swings 115 inward to carry the upper shuttle into the shuttle-box, the lever 69, pivotally supported on the bracket 70, secured to the frame of the loom, has the forked end 71 engaged with the pin 72 on the shuttle-carrier 38, and the opposite end, provided with the spring-pawl 73, is moved into the position shown in broken lines when the shuttle-carrier swings inward 120 to place a shuttle into the shuttle-box and 125 130

is moved into the position shown in solid lines when the shuttle-carrier swings forward after delivering the shuttle, and the spring-pawl, which has yielded to and passed over 5 the projection 74 on the shield 65, engages with the same and carries the shield over the tooth of the ratchet-wheel 59 and permits the pawl 61 to engage with the tooth to turn the shaft 39 and operate the chains to move the 10 shuttles 44 forward. As the shaft 39 must be turned exactly one-quarter turn to move the advance shuttle into the exact position required to carry it into the shuttle-box and raise it out of the spring-clamps 43 by the 15 closing of the gate 18 of the shuttle-box, and as the mechanism for operating the shaft 39 is liable to wear, I secure to the shaft the disk 75, having at equal distances apart four concave seats 76, and pivotally secure to the 20 arm 77 of the bracket 78 the lever-arm 79, provided at its lower end with the roller 80, the peripheral surface of which coincides with the concave seats 76, and I also secure the coiled spring 81 at one end to the lever- 25 arm 79 and at the other end to a fixed part of the machine. The spring 81 is of sufficient strength to force the roller 80 into the concaved seats 76 when it has partially entered the same, and thereby overcomes any 30 wear or backlash in the operating mechanism.

Having thus described my invention, I claim as new and desire to secure by Letters Patent—

1. In a loom, the combination of the following instrumentalities: a lay, a shuttle-box 35 open in the front for the insertion of the shuttle and open in the bottom for the discharge of the shuttle, a gate normally closing the latter opening and forming the bottom of the 40 shuttle-box, a swell in the upper side of the shuttle-box connected with the gate, a filling-detector, and actuating mechanism between the filling-detector and the gate, whereby, when a filling-thread is exhausted or broken, 45 the gate is opened and the faulty shuttle ejected, as described.

2. In a loom, the combination of the following instrumentalities: a lay, a shuttle-box having an opening in the front for the insertion 50 of the shuttle and an opening in the bottom for the discharge of the shuttle, a hinged gate forming the bottom of the shuttle-box and in the normal position closing the opening in the bottom, a deflector on the top of the 55 shuttle-box, connections between the deflector and the gate, a filling-detector, and actuating mechanism, substantially as described, whereby, when the filling-thread is broken or exhausted, the gate is released, the deflector 60 enters the top of the shuttle-box and the faulty shuttle is ejected, as described.

3. In a loom, the combination of the following instrumentalities: a lay, a shuttle-box on the lay, the shuttle-box having an opening 65 in the front for the insertion of the shuttle and an opening in the bottom for the discharge of the shuttle, a gate, pivotally connected

along its rear side, normally closing the opening in the bottom of the shuttle-box, a shuttle-carrier, a filling-detector, and actuating mechanism controlled by the filling-detector; whereby, when the filling is broken or exhausted, the gate is operated, the faulty shuttle is ejected and a fresh shuttle is carried over the gate and lifted into the shuttle-box, 75 as described.

4. A loom containing the following instrumentalities: a lay having a shuttle-box open in the front for the insertion of the shuttle, a passage for the discharge of the shuttle in 80 the bottom of the shuttle-box, a gate hinged on one side normally closing the said passage and directing the discharge of the shuttle when opened, a shuttle-carrier, adapted to carry a series of reserve shuttles, pivotally 85 supported from below, a filling-detector, and actuating mechanism whereby, when a change of shuttles is required, the shuttle-carrier is operated to swing toward the lay and carry a shuttle into the shuttle-box, as described. 90

5. A loom containing the following instrumentalities: a lay, a shuttle-box on the lay open on the front for the insertion of the shuttle, a hinged gate forming the bottom of the shuttle-box, a shuttle-carrier supporting 95 a series of reserve shuttles pivotally supported and adapted to swing toward and from the lay, the filling-detector, and the mechanism connecting the same with the gate, and actuating mechanism, whereby, when a change of 100 shuttles is required, the shuttle-carrier is operated to swing toward the lay to carry the foremost shuttle into the shuttle-box, and the shuttle is lifted off from the shuttle-carrier by the closing gate, as described. 105

6. A loom containing the following instrumentalities: a lay, a shuttle-box on the lay having an opening in the front for the insertion of the shuttle, a hinged gate forming the bottom of the shuttle-box, a shuttle-carrier 110 forming the support of a series of reserve shuttles pivotally supported near its lower end, a filling-detector, the connections from the filling-detector to the gate, and actuating mechanism controlled by the filling-detector; 115 whereby on the breaking, or exhaustion, of the filling the faulty shuttle is ejected and replaced by a new shuttle, as described.

7. In a loom, the combination with the lay, a shuttle-box on the lay having an opening 120 in the front for the insertion of the shuttle, of a shuttle-carrier pivotally supported and adapted to swing parallel with the lay, a shuttle-support consisting of endless chains thereon, a filling-detector, and actuating mechanism controlled by the filling-detector; whereby, when a new shuttle has been placed into the shuttle-box, the shuttles on the shuttle-support are carried forward as the shuttle-carrier swings into its normal position, as 125 described.

8. In an automatic shuttle-supplying mechanism for looms, a shuttle-support consisting of two endless chains supported on sprocket-

wheels adapted to carry a series of reserve shuttles, a bracket, pivotally supported near its lower end, carrying the sprocket-wheels and chains, a filling-detector comprising a 5 weft-fork, the lay, the shuttle-box and actuating mechanism controlled by the weft-fork of the loom; whereby the reserve shuttles are carried forward to the point of delivery and are swung toward the lay to carry the 10 most shuttle into the shuttle-box, as described.

9. In a loom, in combination, the following instrumentalities: a lay having a shuttle-box provided with an opening in its front for the insertion of the shuttle, a gate pivotally 15 supported on one side of and forming the bottom of the shuttle-box, a filling-detector, a rock-shaft operated through the filling-detector, a latch securing the gate in the normal position, an arm on the rock-shaft and actuating mechanism operated by the arm; whereby, when a filling breaks or runs out, the latch is operated to release the gate, and the faulty shuttle is ejected, as described.

10. In a loom, in combination, a lay having 20 a shuttle-box provided with an opening in its front for the insertion of the shuttle, a hinged gate forming the bottom of the shuttle-box, a deflector on the top of the shuttle-box, a swell in the top of the shuttle-box, connections 25 between the gate and the swell and the gate and the deflector, and actuating mechanism controlled by the weft-fork; whereby, on the breaking or the exhaustion of the filling, the gate is released and operates the swell and carries the deflector into the shuttle-box to discharge the spent shuttle, as described.

11. In a loom, in combination, a lay, a shuttle-box on the lay provided with an opening 40 in the front for the insertion of the shuttle, a gate closing an opening for the discharge of the faulty shuttle and forming the bottom of the shuttle-box, a deflector connected with and operated by the gate, a swell on the top 45 of the shuttle-box, the weft-fork, connections between the weft-fork and the gate, connections between the gate and the swell, a shuttle-carrier pivotally mounted to swing toward and from the lay, and actuating mechanism 50 controlled by the weft-fork; whereby the gate is opened, the deflector operated to discharge the shuttle, the swell is raised and a new shuttle is inserted when the filling is broken, or exhausted, as described.

55 12. In a loom, in combination, the lay, a shuttle-box on the lay having an open side, a gate hinged on one side and forming the bottom of the shuttle-box, a latch for holding the gate in the normal closed position, a bell-60 crank lever, a cam on the cam-shaft, a roller on the gate bearing on the bell-crank lever, a shuttle-carrier pivotally mounted, the weft-fork, and connections therefrom to operate the parts, and actuating mechanism, whereby, 65 when the defective shuttle is expelled, the shuttle-carrier is made to swing toward the lay and, as the lay swings forward, the bell-

crank lever raises the gate and closes the same under the shuttle carried into the shuttle-box by the swinging of the shuttle-carrier 70 as the lay approaches the forward limit of its stroke, as described.

13. In a loom, in combination, a lay, a shuttle-box, on the lay, open on one side, a shuttle-carrier pivotally supported at its lower 75 end on a shaft to swing toward and from the lay, a cam on the cam-shaft, an arm secured to a lever operated by the cam to impart continuous reciprocating motion to the arm, a seat on the arm, a detector rock-shaft, connections between the detector rock-shaft and the arm, and connections by means of the seat between the arm and the shuttle-carrier; whereby, when a shuttle has been ejected and a new shuttle is required to be placed into 80 the shuttle-box, the shuttle-carrier is swung to deliver the shuttle into the shuttle-box, as described.

14. In a loom, the combination with the lay, a shuttle-box on the lay open on its front side 85 for the insertion of a shuttle, of a shaft extending from the end frame below the lay and parallel with the lay, a shuttle-carrier pivotally supported on the shaft to swing toward and from the lay, the endless chains, sprocket-wheels, the two shafts, mounted on the carrier forming the support of the reserve shuttles, a sprocket-wheel secured to one of the shafts supporting the endless chains, a sprocket-wheel on the shaft supporting the 90 carrier, a chain connecting the two sprocket-wheels, and actuating mechanism, substantially as described, whereby, when a shuttle has been placed into the shuttle-box, the 95 reserve shuttles on the shuttle-supporting 100 chains are advanced, as and for the purpose described.

15. In a loom, the combination of the following instrumentalities: a lay, a shuttle-box 105 on the lay open in front for the insertion of a shuttle, a hinged gate forming the bottom of the shuttle-box, a deflector, and a binder-swell on the top of the shuttle-box connected with and operated by the gate, a shaft extending from the end frame, a shuttle-carrier 110 pivotally mounted on the shaft, having two endless chains mounted on two shafts provided with sprocket-wheels and forming the support for the reserve shuttles, the weft-fork, the cams and the cam-shaft, actuating 115 mechanism controlled by the weft-fork and operated through cams on the cam-shaft; whereby, on the breaking or exhaustion of the filling, a new shuttle is placed into the 120 shuttle-box and the reserve shuttles are advanced to bring one into the position for placing it into the shuttle-box, as described.

In witness whereof I have hereunto set my hand.

WINFIELD S. THOMAS.
